APPARATUS FOR DRAFTING TEXTILE FIBRES
Geoffrey Hill Ambler, Ilkley, England, assignor to Ambler Superdraft Limited, Ilkley, England, a British company

Filed Oct. 24, 1960, Ser. No. 64,415

Claims priority, application Great Britain Nov. 27, 1959
6 Claims. (Cl. 19—287)

This invention relates to apparatus for drafting textile fibres in the form of rovings or the like, the apparatus being of the kind in which an intermediate unit is mounted on the apparatus between feed and drafting rollers for slidable movement in a direction transverse to that of movement of the roving or the like, and means are provided for reciprocating the unit so as to traverse the roving or the like passing through the unit across the drafting rollers, the purpose of such traversing movement, in general, being to avoid localised wear of the drafting rollers as would occur if the yarn emerging from the nip of such rollers due to the drafting action were continuously to engage the same circumferential line on the rollers, one of which is usually formed from non-metallic material, e.g., a granulated cork compound, and is thus particularly prone to such localised wear. Such wear is generally known as "roller nicking," and interferes with the drafting action, particularly when drafting to a high degree, e.g., at drafts of 50, 100 or more, when precise grabbing action of the rollers on the fibres is necessary. Consequently, it has been found necessary to replace or re-grind the non-metallic drafting rollers at frequent intervals to ensure efficient drafting action, and this is generally inconvenient and expensive.

Although such wear is reduced considerably by the traversing movement referred to above, it still persists at the circumferential lines on the roller surface corresponding to the limits of the traversing movement, because of the short dwell at each end of the movement occasioned by the taking up of the inevitable working clearances necessary in the traversing mechanism, such clearances becoming greater as normal wear takes place.

An object of the invention is to provide a traversing mechanism which reduces still further the roller nicking arising from such dwell at the limits of the traversing movement.

According to the present invention, there is provided a drafting apparatus of the kind referred to, wherein the traversing mechanism comprises a stationary internal gear secured to the drafting apparatus, a driving shaft arranged co-axially with the internal gear, a first eccentric secured to the driving shaft, an external gear freely mounted on the first eccentric and adapted to mesh with the internal gear, and a second eccentric or a cam secured to the external gear and adapted to engage an abutment connected to the intermediate unit.

By these means, upon rotation of the driving shaft, the axis of the pinion is caused to gyrate about the axis of the driving shaft, while at the same time, the pinion rolls around the internal gear and is driven by that gear to cause rotation of the second eccentric. Such motions produce a reciprocation of the intermediate unit that varies in amplitude so that the point of reversal of the traversing yarn on the drafting roller surfaces varies from one stroke to another of the traversing mechanism, and the wear thus takes place at a number of different points over the roller surface. It is preferable that the eccentricities of the two eccentrics are slightly different in magnitude.

It is, of course, preferable that the reversal should take place at as many different points on the roller surface as possible before taking place at any point a second time, thus spreading the wear as evenly as possible over the

2

width of the drafting rollers. Though considerations of space, complication of design and cost, limit to some extent the degree of variation to be obtained, one example of a traversing mechanism according to the invention that has been found to give satisfactory results both as regards the quality of drafting and the useful life of the drafting rollers will now be described in greater detail with reference to the accompanying diagrammatic drawings, in which—

10 FIGURE 1 is a sectional elevation of part of a drafting apparatus,

FIGURE 2 is a view of part of the apparatus shown in FIGURE 1 as seen in the direction of the arrow in FIGURE 1 and drawn to a somewhat larger scale than FIGURE 1, and

15 FIGURE 3 is a diagram illustrating the trace "pattern" of the traversing yarn.

A roving 11 is passed through the nip of a pair of feed rollers 12 and 13 and through a roving guide 14 to the 20 nip of a pair of intermediate rollers 16 and 17, and from there through a channel-shaped member 18 to the nip of a pair of drafting rollers 19 and 21 from which it passes in the form of a yarn 22 to the bobbin of a spinning device of known construction.

25 The roving guide 14, intermediate rollers 16 and 17, channel-shaped member 18 and gearing for driving the intermediate rollers are mounted in an intermediate unit indicated generally in FIGURE 1 by reference numeral 24.

The main framework 26 of the unit 24 is formed with 30 a semi-circular bearing surface 27 arranged to rest on the upper surface of a bearing member 28 forming part of the drafting apparatus, the bearing member being secured to a support 29. The unit 24 is attached to a pair of supports 31 forming part of a saddle member 32 by means of a pair of pins 33 slidably mounted in the framework 26 and arranged to engage a corresponding pair of holes in the supports 31. The pins 33 are actuated by a pair of leaf-spring members 34 secured to the framework 26, the pins 33 being reduced at 36 to form a pair of spaced 35 shoulders, the reduced portions 36 passing through suitable key-hole slots (not shown) in the leaf-spring members 34.

The saddle member 32 is one of a series each supporting a unit 24, as indicated in FIGURE 2, and each saddle member 32 is mounted on an extension 37 of the corresponding bearing member 28 (one of which is provided for each unit) by means of a pair of rods 38 and 39, the rods 38 being secured to their respective saddle members while the rod 39 is common to the series of saddle members. The rods 38 and 39 are slidably mounted in the extensions 37 and the saddle members are positioned by means of a series of pins 41 projecting from the rod 39.

The saddles 32 are traversed by the rod 39 on which is secured by means of a pair of depending brackets 42 a traversing frame 43.

55 A shaft 47 is rotatably mounted in a housing 48 secured to the support 29. Secured to the shaft 47 is a wormwheel 49 arranged in mesh with a worm 51 secured to a shaft 52 rotatably mounted in the end bearing members 28 of a series and constituting the common driving shaft for the 60 series of units.

The shaft 47 is formed with an eccentric 46 on which is freely mounted an external gear 53 arranged in mesh with an internal gear 54 secured against rotation in the housing 48 co-axially with the shaft 47. Formed integrally with the gear 53 is a second eccentric 56 arranged between a pair of abutment faces 44 secured to the traversing frame 43, the eccentric 56, during rotation, pressing alternately on the abutment faces 44 to cause reciprocation of the traversing frame.

70 It will thus be seen that, upon rotation of the shaft 47, the traversing frame 43 together with the rod 39 is reciprocated in the extensions 37, thus causing the saddle

members 32 to traverse through the action of the pins 41.

In this example, the internal gear 54 has twenty-one teeth and the external gear seventeen teeth, and the combined effect of this ratio and the motions of the two eccentrics 46 and 56 is to produce a trace "pattern" (see FIGURE 3) of the traversing yarn on the surface of the drafting rollers that varies in amplitude and point of reversal from one stroke to another until the driving shaft has made seventeen revolutions in one direction during which time the second eccentric has made four revolutions in the opposite direction. It will be seen that the "pattern" repeats only after every seventeenth revolution of the driving shaft with the result that wear is well spread over the width of the drafting rollers.

The spreading of the wear in this manner is enhanced by providing that the point of reversal of the traversing yarn on the surface of the drafting roller is not allowed to occur in the same place more than once within the "pattern." This is achieved by providing that the eccentricity of the eccentric 46 is greater than that of the eccentric 56. In this example, it is found that satisfactory results are obtained by such a difference in eccentricity amounting to about $\frac{1}{64}$ ".

A plurality of sections of units 24 as described above are arranged along the length of the spinning frame, common driving shafts 52 being connected by suitable couplings and driven by gearing connecting one end shaft to a suitable driving member on the spinning frame. Each section is thus complete in itself, having its own driving shaft for the various units in the section and its own traversing gear.

I claim:

1. A drafting apparatus of the kind referred to, in which an intermediate unit is mounted on the apparatus between feed and drafting rollers for slidable movement in a direction transverse to that of movement of the roving or the like, and traversing mechanism is provided for reciprocating the unit, said traversing mechanism comprising a stationary internal gear secured to the drafting apparatus, a driving shaft arranged co-axially with the internal gear, a first eccentric secured to the driving shaft, an external gear freely mounted on the first eccentric and adapted to mesh with the internal gear, at least two abutments connected to the intermediate unit and a second eccentric member secured to the external gear and adapted to engage said abutments to effect the traversing movement.

2. A drafting apparatus of the kind referred to, in which an intermediate unit is mounted on the apparatus between feed and drafting rollers for slidable movement in a direction transverse to that of movement of the roving or the like, and traversing mechanism is provided for reciprocating the unit, said traversing mechanism comprising a stationary internal gear secured to the drafting apparatus, a driving shaft arranged co-axially with the internal gear, a first eccentric secured to the driving shaft, an external gear freely mounted on the first eccentric and adapted to mesh with the internal gear, at least two abutments connected to the intermediate unit and a second eccentric member secured to the external gear and adapted to engage said abutments to effect the traversing movement, the eccentricities of the first eccentric and the second eccentric member being slightly different in magnitude.

3. A drafting apparatus of the kind referred to, in which an intermediate unit is mounted on the apparatus between feed and drafting rollers for slidable movement in a direction transverse to that of movement of the roving or the like, and traversing mechanism is provided for reciprocating the unit, said traversing mechanism comprising a

stationary internal gear secured to the drafting apparatus, a driving shaft arranged co-axially with the internal gear, a first eccentric secured to the driving shaft, an external gear freely mounted on the first eccentric and adapted to mesh with the internal gear, at least two abutments connected to the intermediate unit and a second eccentric member secured to the external gear and adapted to engage said abutments to effect the traversing movement, the eccentricity of the first eccentric being greater than that of the second eccentric member.

4. A drafting apparatus of the kind referred to, in which an intermediate unit is mounted on the apparatus between feed and drafting rollers for slidable movement in a direction transverse to that of movement of the roving or the like, and traversing mechanism is provided for reciprocating the unit, comprising a series of intermediate units mounted on a common supporting member slidably mounted for traversing movement in a supporting framework, and wherein the traversing mechanism comprises a stationary internal gear secured to the drafting apparatus, a driving shaft arranged co-axially with the internal gear, a first eccentric secured to the driving shaft, an external gear freely mounted on the first eccentric and adapted to mesh with the internal gear, at least two abutments on the supporting member and a second eccentric member secured to the external gear and adapted to engage said abutments to effect the traversing movement.

5. A drafting apparatus of the kind referred to, in which an intermediate unit is mounted on the apparatus between feed and drafting rollers for slidable movement in a direction transverse to that of movement of the roving or the like, and traversing mechanism is provided for reciprocating the unit, comprising a series of intermediate units mounted on a common supporting member slidably mounted for traversing movement in a supporting framework, and wherein the traversing mechanism comprises a stationary internal gear secured to the drafting apparatus, a driving shaft arranged co-axially with the internal gear, a first eccentric secured to the driving shaft, an external gear freely mounted on the first eccentric and adapted to mesh with the internal gear, at least two abutments on the supporting member and a second eccentric member secured to the external gear and adapted to engage said abutments to effect the traversing movement, the eccentricities of the first eccentric and the second eccentric member being slightly different in magnitude.

6. A drafting apparatus of the kind referred to, in which an intermediate unit is mounted on the apparatus between feed and drafting rollers for slidable movement in a direction transverse to that of movement of the roving or the like, and traversing mechanism is provided for reciprocating the unit, comprising a series of intermediate units mounted on a common supporting member slidably mounted for traversing movement in a supporting framework, and wherein the traversing mechanism comprises a stationary internal gear secured to the drafting apparatus, a driving shaft arranged co-axially with the internal gear, a first eccentric secured to the driving shaft, an external gear freely mounted on the first eccentric and adapted to mesh with the internal gear, at least two abutments on the supporting member and a second eccentric member secured to the external gear and adapted to engage said abutments to effect the traversing movement, the eccentricity of the first eccentric being greater than that of the second eccentric member.
